UNITED STATES PATENT OFFICE

172,536

LEAD SPRAY GUN

Oscar W. Hart, Compton, Calif.

Application October 12, 1951, Serial No. 16,926

Term of patent 3½ years

(Cl. D62—2)

To all whom it may concern:

Be it known that I, Oscar W. Hart, a citizen of the United States of America, residing in the city of Compton, county of Los Angeles, State of California, have invented a new, original, and ornamental Design for a Lead Spray Gun, of which the following is a specification, reference being had to the accompanying drawing, forming a part thereof.

In the drawing:

Figure 1 is an elevational view from the side of a lead spray gun, showing my new design.

Figure 2 is a top plan view of the gun shown in Figure 1.

Figure 3 is a front elevational view of the gun shown in Figure 1, and

Figure 4 is a rear elevational view of the gun shown in Figure 1.

I claim:

The ornamental design for a lead spray gun, as shown.
